UNITED STATES PATENT OFFICE.

PETER SCHOEN, OF ALLEGHENY, PENNSYLVANIA.

STEAM-VALVE.

SPECIFICATION forming part of Letters Patent No. 614,311, dated November 15, 1898.

Application filed November 29, 1897. Serial No. 660,086. (No model.)

To all whom it may concern:

Be it known that I, PETER SCHOEN, a citizen of the United States of America, residing at Allegheny, in the county of Allegheny and 5 State of Pennsylvania, have invented certain new and useful Improvements in Steam or Air Valves, of which the following is a specification, reference being had therein to the accompanying drawings.

10 This invention relates to certain new and useful improvements in valves, and relates particularly to that class of valves employed on steam-engines and the like.

The invention aims to construct a valve of 15 this nature wherein the ordinary steam-chest will be dispensed with, and in lieu of the ordinary slide-valve employed to move longitudinally through the steam-chest and alternately open and close the steam-ports I provide a valve having a rotary motion.

20 The invention further aims to construct a valve which may be arranged, if desired, with a pressure-cylinder communicating with the port which serves the purpose of the steam-chest, and it further aims to provide means 25 for cushioning the piston operating in the steam-cylinder.

In describing the invention in detail reference is had to the accompanying drawings, 30 forming a part of this specification, and wherein like letters of reference indicate similar parts throughout the several views, in which—

35 Figure 1 is a longitudinal sectional view of a portion of a cylinder with my improved valve in cross-section. Fig. 2 is a sectional view on line X X of Fig. 1, the pressure-cylinder being removed. Fig. 3 is a perspective view of the cylinders and valve arranged thereon, the latter being partly broken away.

40 Fig. 4 is a side view of the valve. Fig. 5 is a cross-sectional view of the same, and Fig. 6 is a perspective view.

45 Referring now to the drawings by reference-letters, *a* indicates an ordinary steam-cylinder, and *b* a steam-chest secured thereto in the ordinary manner. The cylinder is provided with the ordinary exhaust-port *c* and with the auxiliary ports *d d'*, these latter opening into the steam-passages *e e'* to each end of 50 the cylinder.

Within the steam chest or casing *b* is arranged an auxiliary chest or casing *b'*, which

is provided with openings *b²*, *b³*, and *b⁴* at its base and which rests upon the flanges *f*, provided therefor on the cylinder-casing. 55 This auxiliary casing or chest is provided at its top with a port *g*, communicating with the port *g'* between the two casings. The outer casing *b* is also provided with a port *g²* directly above the port *g*, to which is connected 60 a pressure-cylinder *g³*, that is or may be provided with a removable cap *g⁴* on its top.

Arranged within the auxiliary casing *b'* is the valve *h*, cylindrical in form, and which is fitted neatly within the said casing *b'*. This 65 valve is provided on its one end with a stem *h'*, which protrudes through the end of the casing *b* and has secured to its end the crank *h²*, to which the valve-stem is attached for operating the valve. This valve *h* is provided with a longitudinal opening *h³*, by which the steam is admitted to its central opening *h⁴* from the port *g'*. The valve is also provided along its underneath side with a groove *k*, communicating with the exhaust-port *c* 70 and from which the steam is exhausted at its outlet-port *c'*. Longitudinal openings *k' k²* are provided in the valve *h*, these being of the same length as the larger opening *h³*, and they communicate with the ports *d* and *d'*, by 75 which steam is admitted to the ports *e* and *e'* to the cylinder. These openings *k' k²* are so arranged as to register alternately with the ports *d* and *d'* as the valve is reversed and the intervening spaces of the valve between 80 the said openings and the groove in its underneath side, and which forms a port of the exhaust, thus forms the top of the valve by which the aforesaid openings are alternately opened and closed.

85 The steam is admitted into the chest or port *g'* and passed through the port *g*, opening *h³*, into the valve, from which point (providing the ports *k'* and *d* register) it passes to the port *e* and into the cylinder. If, however, the 90 valve is reversed and the ports *k²* and *d'* register, the port *d* is closed and the steam passes through the port *e'* to the cylinder at the opposite end from that by which it passed through the port *e*. As the lap of the valve 95 passes off the ports *d* or *d'* to open the same it will be observed that only one-half of the port *d* or *d'* is opened, at which time the piston has traveled one-half its distance within 100

the cylinder, its movement in the one direction being completed when the valve is reversed and the lap thereof is repassing over the port d or d' , as the case may be.

5 By rotating the valve h an absolute cut-off of the steam is accomplished and the ports are alternately opened and closed with a precision and regularity not accomplished with the ordinary slide-valve.

10 Having fully described my invention, what I claim as new, and desire to secure by Letters Patent, is—

15 In a rotary valve, a steam-chest, a pressure-cylinder secured to said steam-chest and communicating therewith, an auxiliary chest or casing arranged within said steam-chest and provided with a series of openings, said auxiliary chest or casing being suitably secured to flanges carried by the cylinder-casing and being provided at its top with an opening registering with an opening in said pressure-cylinder, a rotary valve arranged

20 within said auxiliary chest or cylinder, and carrying on one end a stem, said stem protruding through the end of the steam-chest, 25 a longitudinal opening h^3 formed in the top of said valve to admit steam, longitudinal openings k', k^2 , formed in the lower portion of said valve, ports d and d' communicating with said openings k', k^2 whereby steam is admitted to the steam-cylinder, a groove formed in the lower face of said valve whereby the exhaust-steam escapes alternately through the ports e and e' to the port c , and means carried by the stem to reverse the valve at the 30 end of the stroke of the piston, substantially as shown and described.

25 In testimony whereof I affix my signature in presence of two witnesses.

PETER SCHOEN.
